United States Patent Office

Des. 210,351
Patented Mar. 5, 1968

210,351

BOTTLE

Brooks D. Fuerst, Toledo, Ohio, assignor to Owens-Illinois, Inc., Toledo, Ohio, a corporation of Ohio

Filed July 12, 1967, Ser. No. 7,774

Term of patent 14 years

(Cl. D9—87)

FIG. 1

The side not shown is the same in appearance as the side shown.

The characteristic features of this design reside in the configurations shown in full lines on the drawings.

I claim:

The ornamental design for a bottle, substantially as shown and described.
